FIG. 2.

UNITED STATES PATENT OFFICE.

ARTHUR W. SMITH, OF NEW YORK, N. Y., ASSIGNOR TO REMINGTON TYPEWRITER COMPANY, OF ILLION, NEW YORK, A CORPORATION OF NEW YORK.

TYPE-WRITING MACHINE.

1,220,467.

Specification of Letters Patent. Patented Mar. 27, 1917.

Original application filed April 8, 1915, Serial No. 19,871. Divided and this application filed November 14, 1916. Serial No. 131,201.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

10 My present invention relates to improvements in paper controlling devices for type-writing machines, and more particularly to differential or denominational side gage mechanism, the principal object of the invention being to provide new and improved mechanism of the character specified.

To the above and other ends my present invention consists in the features of construction, combinations of devices and arrangements of parts, hereinafter described and particularly pointed out in the claims.

The present application is a division of my prior application Sr. No. 19,871, filed April 8, 1915.

25 The preferred form of the invention has been applied to a No. 11 Remington front strike typewriting machine and is illustrated in the accompanying drawings, wherein—

30 Figure 1 is an enlarged fragmentary plan view showing the carriage of the machine with my invention applied thereto.

Fig. 2 is a fragmentary end view showing the upper part of the said machine.

Fig. 3 is a transverse sectional view taken on a plane indicated by the dotted line $\alpha\alpha$ in Fig. 1 and looking in the direction of the arrows.

0 Figs. 4, 5 and 6 are detail views of the denominational side gage mechanism, Fig. 4 being a front elevation thereof, Fig. 5 being a plan view partly in section, and Fig. 6 a perspective view of a part hereinafter referred to as a friction plate.

Referring to Figs. 1 and 2, the main frame of the machine is shown as comprising a top plate 3, from which rise fixed lugs or standards 4 and 5 whereto are attached front and rear grooved guide rails 6 and 7, which respectively coöperate through anti-friction balls 8 with the front bar 9 and rear bar 10

of a rectangular carriage frame or truck, which further comprises connecting end bars 11. Journaled in the end bars is the axle 12 of a platen 13, said platen being equipped with line spacing mechanism of ordinary Remington construction, comprising a ratchet wheel 66 operatively connected to the right-hand end of the platen. The paper feeding mechanism of the machine comprises feed rollers 77 mounted on a shaft 60 78 which is supported on arms 79 provided with collars 80 which bear loosely on a sleeve 81 mounted to turn on a rock shaft 82. Said rock shaft extends from end to end of the platen and is supported on parallel end bars 65 83 arranged inside the end bars 11 and connected under the platen by a cross bar 84. The bars 83 and cross bar 84 constitute a frame which is rigid with the main part of the carriage frame. A paper apron 92 cut 70 out to provide openings for the feed roller sections is mounted on blocks 93 which bear loosely on the sleeve 81. The forward end portion of the apron 92 is provided with a wire frame or extension 95 so that when the 75 apron is moved away from the platen during the feed roller releasing operation, as explained in my prior application aforesaid, the frame 95 coöperates with the platen to provide a wide opening or throat through 80 which sheets may be readily introduced from the front. A paper table 123 of ordinary construction extends the full length of the platen at the rear side thereof. Adjustably mounted on the table 123 at its left-hand 85 side is a side edge gage 131. This gage is in a vertical plane and is provided with an angular extension or tongue 132 which slidably engages in a grooved track 133 riveted to the upper face of the table 123. The 90 construction is such that the gage or guide 131 is frictionally held in adjusted positions lengthwise of the platen. It is intended to coöperate with sheets, introduced at the rear of the platen, such as wide record sheets. 95

A paper controlling or pressure bail is provided, which is supported on ears 134 rigidly mounted on the front bar of the carriage and perforated to receive pintles 135 at the ends of a square rod or rock shaft 136. 100

Fixed to said square shaft near its ends and projecting rearward are arms 137 to the end portions of which are pivoted at 138 ears 139 rigid with supplementary arms 140 which curve upward and rearward and are connected at their free ends by a round rod or bar 141. Adjustably mounted on the rod 141 are rubber covered pressure rolls 142 which coöperate with the front upper portion of the platen to hold the paper above the printing line. The detailed construction and operation of the bail are described and explained in my said application Serial No. 19,871.

The two-part bail frame, among other purposes, provides a support for denominational or variable side gage devices, to which my present divisional application more particularly relates. Said devices are mounted at the left end of the main part of the bail frame, being supported on a bar or plate-like arm 170 which is arranged just inside the left-hand arm 137 and extends rearward parallel therewith. The forward end of the bar or support 170 is notched or slotted to fit over the square shaft 136 while the rear end of said bar is fixed to said arm 137 by a headed screw 171 which passes transversely through the arm 137 and is threaded into the bar 170. The construction is such that the arm 170 is held in rigid relationship with the arm 137 and the frame of which it is a part. The bar 170 terminates at or near the left of the platen and of the paper apron so that the rear portion of said bar 170 may act as a side gage. In addition the bar provides a support for a plurality or set of variably settable gages, three in the present instance, although of course the number may be varied. Said gages or devices, which are arranged side by side are in the form of slides, blades or bars 172, 173 and 174 of a thickness corresponding to the distance of a letter space movement of the carriage. Said blades, as will be best understood from Figs. 3 and 5, are slotted as indicated at 175 to receive two headed screws 176 which pass leftward through the slots 175 and are threaded into the bar 170, thus slidably securing said blades 172, 173 and 174 to the bar or support 170. The blades 172-174 may be moved or slid backward and forward along the supporting screws 176 and in substantial vertical planes transverse of the platen to an extent limited by the ends of the slots 175 which are adapted to engage with said screws to limit such movement. This slidable movement is for the purpose of moving said blades, gages or devices 172-174 into and out of operative position. The relationship of said gages or slides in respect to each other, considered lengthwise of the platen, never varies, however, but always remains constant as does

also their relationship to the platen, considered lengthwise thereof. In order to prevent the slides or blades from being accidentally displaced after they have once been set, it is preferred to provide devices in the form of friction plates 177 and which, when made, are slightly bent or curved (Fig. 6). These plates or devices are arranged between the slides and are themselves prevented from sliding movements by the screws 176 which pass through round holes 178 in said plates. It will be understood that when the plates are flattened out by tightening the screws 176, they will take up all looseness in the slides and will exert sufficient friction to prevent accidental movement thereof while allowing a ready back and forth adjustment of said slides. Such adjustments are conveniently accomplished by means of keys or finger pieces in the form of cylindrical buttons 179 suitably secured to the tops of the slides. In order not to interfere with each other the buttons are spaced apart lengthwise of the slides, the middle button being at the middle of its slide and the other two buttons at opposite ends of their respective slides. Preferably the tops of the buttons are provided with indicating marks, the right-hand button in the present instance being marked "1", the middle button "10", and the left-hand button "100." These three slides, together with the rear end portion of the bar 170, constitute a variable side gage which is intended to coöperate with work sheets or paper which may be introduced either at the front side or if desired, as may sometimes occur, at the rear side of the platen. The slideable gages are separately effective to position denominational work sheet with which they coöperate so that said sheet may be variably positioned widthwise in any one of a plurality of denominational positions. In the character of work, for example, which is referred to at length in my prior application aforesaid, said work sheet is front fed and is in the form of a check which is adapted to overlie a wide record sheet, which is fed in from the back in coöperation with the gage 131. The checks by the aid of the denominational side gage may be variably positioned, with the result that while the entries on successive checks, whatever their denomination, may always be begun close to the dollar mark on the check, they will nevertheless properly be entered denominational in a single column on the underlying main sheet. This result will follow because while the main sheet remains in an unvarying position lengthwise of the platen, each successive check as it is entered in the machine may be varied denominational in position according to the amount to be written on it, such variation being effected by setting the

proper one of the slides in operative position and gaging the check by it. In this connection it will be borne in mind that the thickness or width of each slide is equal to a letter space movement of the carriage. For example, assuming all of the slides to be set in rearmost position, as in Fig. 1, they will be allowed to remain in this position if the amount on the first check is in units 10 of dollars. If the amount of the second check is in tens of dollars, the "1" slide is drawn forward out of operative position, as shown by the dotted lines in Fig. 5, leaving the "10" slide effective so that the second 15 check will be positioned one unit space to the left of the first check; while if the amount is in hundreds of dollars the "10" slide is also drawn forward, leaving the "100" slide effective. An entry in thousands 20 of dollars will require that all three slides be drawn forward to inoperative position, leaving the rear end portion of the bar 170 to act as a side gage. Greater amounts 25 will of course require the employment of additional slides.

In order to facilitate the movement of the slides or blades forward out of operative position the rear end of the slide 172 has driven into it a headed pin 180, the head whereof 30 overlaps slightly the rear face of the slide 173, while said slide 173 in turn has on its rear end a headed pin 181 which overlaps slightly the slide 174. As a result if all the 35 slides are in rearmost position, as in Fig. 1, and it be desired to render the bar 170 operative as a side gage, it is only necessary to press or pull forward the "100" button 179. If this is done the head of the pin 180 will pick up the slide 173 and the head of the 40 pin 181 will thereupon pick up the slide 174 so that all three slides will be simultaneously moved forward. Similarly the actuation of the "10" button 179 will operate to move forward simultaneously the slides 173 and 45 174. A similar function will be exercised by the devices 180 and 181 if all of the slides are forward in operative position. For example, a rearward push applied to the "1" key will be transmitted through the pin 181 50 to the slide 173 and thence through the pin 180 to the slide 172, causing all three slides to move rearward.

It will be observed that I provide a set of 55 denominational side gages, stops or guides which are arranged in a permanent group so that their distance from each other lengthwise of the platen is always permanent or constant, said gages being fixedly spaced apart; that said gages in the present instance 60 are separately key controlled, these gages being arranged side-by-side and slidably mounted so that they may be moved into and out of operative position transversely of the platen; that said gages are so located in re-

spect to one end of the platen that when in 65 operative position the throwing-off of the paper apron or guide will open a throat or way for the introduction of the work sheet or check which may be front-fed with its left edge coöperative with the selected 70 denominational gage; and that the denominational gage mechanism is equally effective for coöperation with a work sheet that is introduced at the rear side of the platen and pushed or fed forward to the front. 75

Various changes may be made without departing from my invention.

What I claim as new and desire to secure by Letters Patent, is:

1. In a typewriting machine, the combination of a platen, and denominational side gage devices, said devices being arranged in a permanent group and spaced a predetermined distance apart lengthwise of the platen and being separately adjustable to co- 80 operate with the side edge of the paper as it is fed over the platen to provide for a variation in the relationship between the paper 85 and the platen.

2. In a typewriting machine, the combination of a platen, a set of denominational side gage devices for coöperation with one work sheet to position it denominational lengthwise of the platen, said devices being separately settable to vary the position of the 90 paper lengthwise of the platen, and a separate side gage for coöperation with another work sheet.

3. In a typewriting machine, the combination of a platen, and denominational side 100 gage devices comprising a plurality of gages or stops arranged side by side and having an unvarying relationship with each other lengthwise of the platen, said gages being adapted to coöperate separately with the 105 side edges of work sheets, as they are introduced to vary the relationship between the work sheets and the platen.

4. In a typewriting machine, the combination of a platen, and denominational side 110 gage devices for coöperation with the side edges of work sheets as they are introduced into the machine comprising separate gages or stops movable transversely of the platen, the relationship of said gages to each other 115 considered lengthwise of the platen always remaining constant.

5. In a typewriting machine, the combination of a platen, and a side gage arranged on the forward side thereof and movable in a 120 straight path transversely of the platen into and out of position for coöperation with the side edge of a work sheet when introduced at the front of the machine.

6. In a typewriting machine, the combination of a platen, and denominational side 125 gage devices comprising a plurality of gages arranged a letter space distance apart and

- separately coöperative with the side edges of work sheets as they are introduced into the machine to determine the relationship between said work sheets and the platen.
5. 7. In a typewriting machine, the combination of a platen, and denominational side gage devices comprising a plurality of separate slideable gages and guiding means therefor, each gage provided with a finger piece by which it may be separately set in and out of position to coöperate with the side edges of work sheets when introduced into the machine to determine the relationship between said work sheets and the platen, considered lengthwise of the latter.
10. 8. In a typewriting machine, the combination of a platen, denominational side gage devices comprising a plurality of separate gages each provided with a finger piece by 20 which the associate gage may be separately set in and out of position to coöperate with the side edges of work sheets when introduced into the machine to determine the relationship between said work sheets and the platen, considered lengthwise of the latter, and means for enabling each finger piece to actuate a plurality of gages.
15. 9. In a typewriting machine, the combination of a platen, and a plurality of side gages arranged a letter space distance apart and movable transversely of the platen to coöperate separately with the side edges of work sheets when introduced into the machine to determine the relationship of the work sheets with the platen, the relationship of the gages in respect to each other, considered lengthwise of the platen, always remaining constant.
20. 10. In a typewriting machine, the combination of a platen, a plurality of side gages arranged a letter space distance apart and movable transversely of the platen, and a side gage adjustable lengthwise of the platen.
25. 11. In a typewriting machine, the combination of a platen, a carriage, and a set of stops or blades arranged at one end of the platen and separately movable transversely of the platen to facilitate the introduction of a work sheet at the front side of the platen in proper denominational position, the relationship of said blades lengthwise of the platen always remaining constant.
30. 12. In a typewriting machine, the combination of a platen and a plurality of independently key controlled denominational side gages or guides for coöperation with the side edge of a work sheet to determine its relationship with the platen, the relationship of said gages in respect to each other and considered lengthwise of the platen always remaining constant.
35. 13. In a typewriting machine, the combination of a platen, denominational side gages arranged side by side, and frictional devices interposed between said gages.
40. 14. In a typewriting machine, the combination of a platen, a plurality of side gages or stops arranged side by side, spring plates separating said gages, and means for holding said plates against movement when said gages are adjusted.
45. 15. In a typewriting machine, the combination of a platen, a plurality of side gages or stops arranged side by side for co-operation with work sheets when introduced into the machine, said gages having a constant relationship, considered lengthwise of the platen, and finger pieces or keys for each of said gages.
50. 16. In a typewriting machine, the combination of a platen, a plurality of stop blades arranged side by side and each provided with a separate finger piece or key, 85 and means for connecting said blades so that one key may move a plurality of said blades, said blades being adapted to coöperate with the side edges of work sheets when introduced into the machine to determine the relationship of said work sheets with the platen.
55. 17. In a typewriting machine, the combination of a platen, a plurality of stop blades arranged side by side and each provided with a separate finger piece or key, 95 and a pin mounted on the end of one blade, and overlapping the end of another blade, said blades being adapted to coöperate with the side edges of work sheets when introduced into the machine to determine the relationship of said work sheets with the platen.
60. 18. In a typewriting machine, the combination of a platen, and a plurality of 105 gages or stops arranged denominational in a permanent group and adapted for separate coöperation with the side edges of work sheets to determine the relationship of said work sheets in respect to the platen, considered lengthwise of the platen.
65. 19. In a typewriting machine, the combination of a platen, and a plurality of gages or stops arranged denominational in a permanent group and adapted for separate coöperation with the side edges of work sheets when introduced from the front of the machine to determine their relationship in respect to the platen considered lengthwise of the platen, each of said gages being provided with an indicating device.
70. 20. In a typewriting machine, the combination of a platen, a carriage, a bar on said carriage, guide screws carried by said bar, slotted gage blades mounted on said screws, and friction springs interposed between said blades.
75. 21. In a typewriting machine, the com-

bination with a platen, of a group of adjustable side edge gages denominationaly spaced apart and arranged at the front side of the platen and adapted to coöperate with sheets introduced at the front side of the platen.

Signed at the borough of Manhattan, city
